(Cl. D44—24)

FIG. 1.

FIG. 2.

FIG. 3.

FIG. 4.

To all whom it may concern:

Be it known that we, Winford G. Renard and Robert B. Wiggins, citizens of the United States, residing at Green Bay, in the county of Brown and State of Wisconsin, have invented a new, original, and ornamental Design for a Dispenser for Paper Napkins, of which the following is a specification, reference being had to the accompanying drawing, forming a part hereof.

In the drawing,

Fig. 1 is a side elevational view of a dispenser for paper napkins showing our new design;

Fig. 2 is an end elevational view thereof;

Fig. 3 is a top plan view thereof; and

Fig. 4 is a fragmentary cross-sectional view taken along line 4—4 of FIG. 3.

The dominant features of our design reside in those portions shown in full lines.

We claim:

The ornamental design for a dispenser for paper napkins, substantially as shown and described.
